UNITED STATES PATENT OFFICE.

GUSTAV EGLOFF, OF CHICAGO, ILLINOIS, ASSIGNOR TO UNIVERSAL OIL PRODUCTS COMPANY, OF CHICAGO, ILLINOIS, A CORPORATION OF SOUTH DAKOTA.

PROCESS OF CRACKING PETROLEUM OIL.

Application filed October 22, 1923. Serial No. 669,931.

This invention relates to improvements in process of cracking petroleum oil, and refers more particularly to that type of cracking process in which the oil is passed first 5 through a heating coil and thence to an expansion chamber; the vapors removed therefrom and subjected to reflux condensing action. In this type of process it is desirable to keep the tubes as free as possible from 10 carbon and to accomplish this it is desirable to avoid returning the residuum to the heating coil, inasmuch as the residuum contains the maximum amount of carbon. At the same time residuum is not always completely 15 converted, and it is often desirable to subject the residuum to further cracking conditions of temperature and pressure.

The object of the invention is for the purpose of accomplishing this without stopping 20 up the heating coil and without substantially modifying the present type of apparatus.

The invention will be understood from the following description, reference being had 25 to the accompanying drawing, in which the single figure represents a somewhat dia-grammatic side elevation and vertical sec- 30 tion of an apparatus suitable for carrying out the invention.

Referring to the drawings (1) designates 35 a furnace, in which is mounted heating coil (2) which may take the form of a continuous coil. Raw oil is fed to this coil by the pump (3) through feed line (4) and the heated oil is delivered from the coil to the upper end of expansion chamber (5) by means of transfer line (6) having throttle valve (7). Expansion chamber (5) may take the form of vertically extending cyl- 40 inder (8). The vapors pass out of the upper chamber (5) through line (9) controlled by valve (10) to the dephlegmator (11). This dephlegmator (11) has at its upper end vapor outlet pipe 12 controlled by valve 13 and leading to coil (14) set in condenser box (15). The oil passes out of the condenser coil into the upper end of receiver (16) which latter has gas control valve (17) and liquid control valve (18).

The reflux condensate may be returned directly to the heating coil by means of the pipe (19), controlled by valve (20), leading back to feed pipe (4). The residuum may be drawn off from the lower end of the expansion chamber through pipe (21) having con-

trol valve (22). The residuum then may pass through line (23) having control valve (24) to circulating pump (25) and thence through pipe (26) having valve (27) to the transfer line (6) at a point adjacent where it enters 60 the expansion chamber as shown at (28). Certain of the residuum may be evacuated from the system, if desired, through branch (29) having control valve (30).

As a feature of the invention the uncon- 65 densable gas is mixed with the residuum in the line (26) before the residuum is returned to the expansion chamber. This is accom- 70 plished by means of gas pump (31) and pipe (32) connected to the upper end of the re- ceiver and to the line (26) respectively; a suitable valve (33) being interposed in line (32).

The uncondensable gas is mixed with the 75 residuum in such proportions as to more or less atomize the residuum and thus get a more effective heat transfer between the hot oil from the transfer line (6) and the residuum, and thus produce more effective 80 recracking of the residuum.

By means of the present invention prac- 85 tically all of the oil can be recracked, and in most cases it will not be necessary to withdraw any residue through line (29) but only to clean the coke out of the reaction chamber. This will result, of course, in producing the maximum amount of given oil from the cracking crude and avoid accumulation of 90 liquid residue. The process may be operated at pressures from 100 to several hundreds of 95 pounds or more, and the oil heated to a temperature of 850° F. more or less as it leaves the transfer line.

I claim as my invention:

1. A continuous process of oil conversion 95 comprising advancing a stream of oil through a heating zone wherein it is raised to a cracking temperature, introducing highly heated oil into an enlarged reaction zone wherein a body of oil accumulates and 100 substantial vaporization takes place, dephlegmating the evolved vapors, continuously withdrawing unvaporized residual oil from said reaction zone below the liquid level of the oil therein, introducing to the 105 unvaporized residual oil a portion of the uncondensable gases produced in the process, returning such withdrawn residual oil together with the uncondensable gases intro- 110 duced thereto under pressure directly and

without passage through said heating zone into the vapor space of said reaction zone to undergo further treatment therein, and maintaining a superatmospheric vapor pressure on the oil in said stream and in said reaction zone.

2. A continuous process of oil conversion comprising subjecting an advancing stream of oil to a cracking temperature in a heating zone, passing heated oil from said stream into an enlarged reaction chamber wherein a body of liquid oil accumulates and substantial vaporization occurs, dephlegmating

the evolved vapors, continuously withdrawing unvaporized residual oil from said reaction zone, isolating predetermined portions of such residual oil from the system, uniting with the remaining portions of the residual oil uncondensable gases produced in the process, returning such portion of the unvaporized oil and the uncondensable gases united therewith directly and without passage through said heating zone to the vapor space of said reaction chamber for further treatment. 15 20

GUSTAV EGLOFF.
